(57) **CLAIM**

We claim the ornamental design for a display screen or portion thereof with a graphical user interface, as shown and described.

DESCRIPTION

FIG. 1 is a front view of a display screen or portion thereof with a graphical user interface showing a first embodiment of our new design; and,

FIG. 2 is a front view of an alternate embodiment thereof. The dash-dot broken lines in the drawings illustrate the display screen or a portion thereof while the even broken lines illustrate portions of the graphical user interface. No subject matter in either broken lines form part of the claimed design.
